CLAIM

The ornamental design for paper retainer for a printer stand, as shown.

DESCRIPTION

FIG. 1 is a perspective view from above of the paper retainer for a printer stand of our invention;

FIG. 2 is a side elevational view of the paper retainer of FIG. 1, the other side being the same;

FIG. 3 is a front elevational view of the paper retainer of FIG. 1;

FIG. 4 is a rear elevational view of the paper retainer of FIG. 1;

FIG. 5 is a top plan view of the paper retainer of FIG. 1; and,

FIG. 6 is a bottom plan view of the paper retainer of FIG. 1.
